CLAIM

I claim the ornamental design for a lever action battery terminal, substantially as shown and described.

DESCRIPTION

FIG. 1 is a perspective view showing the front and right side design of the lever action battery terminal;

FIG. 2 is a perspective view showing the top and rear of the FIG. 1 lever action battery terminal;

FIG. 3 is a top plan view of the FIG. 1 lever action battery terminal;

FIG. 4 is a bottom plan view of the FIG. 1 lever action battery terminal;

FIG. 5 is a left side view of the FIG. 1 lever action battery terminal, the right side being the same;

FIG. 6 is a front view of the FIG. 1 lever action battery terminal; and,

FIG. 7 is a rear view of the FIG. 1 lever action battery terminal.
